[57] **CLAIM**

The ornamental design for a tuner with amplifier, as shown and described.

DESCRIPTION

FIG. 1 is a perspective view of a tuner with amplifier showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof; and

FIG. 7 is a rear elevational view thereof; and,

FIG. 8 is a perspective view thereof, wherein the lid portion is in the open position.

The remaining views of the inside of the tuner with amplifier which are not visible in FIG. 8 form no part of the claimed design.
